UNITED STATES PATENT OFFICE.

EUGENE SESSLER, OF CHICAGO, ILLINOIS.

ARCH SUPPORT.

Application filed June 9, 1926. Serial No. 114,600.

This invention relates to a support for the arch of an ailing or weak foot, its purpose being to relieve any suffering thereof, and also to ameliorate conditions which require correction.

For its objects my invention aims to provide a support of the kind described which is simple, light, strong, adjustable, and providing at the necessary points a yielding reinforcement which will produce the maximum benefit to the user. It combines in its structure an arched metal plate on which is rested a top cushion or layer of some such material as leather having an appreciable thickness. The metal plate which extends lengthwise of the cushion is fixedly secured thereto at one end, but at its other end may be adjusted lengthwise longitudinally thereof whereby to vary the height of the arch which is provided. In addition, the cushion is upwardly extended upon the instep side to provide a saddle which exerts a desired pressure upon the arch. Features such as these, as well as others to be hereinafter set forth, characterize my invention of which a preferred embodiment is illustrated in the accompanying drawing in the manner following:

Figure 1 is a top or plan view of the arch support;

Fig. 2 is a longitudinal section therethrough on line 2-2 of Fig. 1;

Fig. 3 is a bottom plan view of the device;

Fig. 4 is a transverse section therethrough on line 4-4 of Fig. 3; and

Fig. 5 is a detail in section taken on line 5-5 of Fig. 1.

The present support combines in its structure an arched metallic plate A which underlies a cushion B preferably of selected sole leather. As appears best in Fig. 3, the plate A which extends longitudinally of the cushion is forked at its forward end to provide a pair of diverging arms 6 each of which is fixedly connected as by rivets 7 with the top cushion near its forward edge. The support is designed to extend from beyond the heel of the foot to a point just forwardly of the ball thereof which latter will bear upon the cushion just rearwardly of the connecting rivets 7.

Rearwardly of the forked arms and substantially midway of its length, the plate is weakened by the provision of slots 8 which extend preferably in a longitudinal direction, as shown in Fig. 3. These slots are

located approximately at the highest point in the arch so as to give a desired flexibility to the support at that point. On the instep side the plate is upwardly curved as at 9 (see Fig. 4) to provide a saddle, the top cushion being similarly curved in consequence. Due to the presence of this saddle a reinforcement is provided for the instep both laterally and upon its under side.

At the rear end of the support an adjustable connection is made between the plate and its cushion. As shown in the drawing this comprises a block 10 which is accommodated in a recess extending longitudinally of the cushion, a flange 11 projecting laterally from the block in flush relation with the upper side of the cushion so as to permit removal of the block from that side only. Formed in this block are a plurality of threaded openings 12 within any one of which may be secured a screw 13 which passes through an opening 14 in the plate to present its flat head flush with the under plate side. By providing several such block openings, spaced apart slightly different than the openings in the arched plate, I am enabled to adjust the cushion support for disposition in various arcs and at various elevations.

With reference to the device in its entirety, it will be noted that the two points of the fork are so shaped and disposed that the ball portion of the foot may rest adjacent thereto in a proper and comfortable position. The tension of the arched plate may be properly adjusted to accord with the weight of the user and with the size of the shoe which is worn. The top cushion is of substantially even thickness throughout, being skived to a thin edge along its front, and also along the top of the saddle, if desired. In use, it will be found that the spring plate, working in conjunction with the top cushion, will afford to the bones of the arch a natural movement and support such as is needful and beneficial in the treatment of weak arches or flat feet. Excess strain to the bones is relieved in this manner, as experience has demonstrated.

I claim:

1. In an arch support, the combination of an elongated spring plate arched lengthwise and provided at its forward end with diverging arms, the plate being slotted in the region of the arch center whereby to increase its flexibility at that point, a cushion supported by the plate and extending thereover

at every point, means fixedly connecting the cushion to the plate at the forward ends of the two arms thereof, and other means adjustably securing the cushion to the plate 5 at a point adjacent the rear end thereof, the curvature of the arch in the plate being variable according to adjustments in the connection between the cushion and plate.

2. A foot appliance having in combination 10 a flexible cushion of uniform thickness adapted to underlie the foot to a point forwardly of the ball thereof, and means providing a yielding reinforcement for the cushion consisting of an elongated spring plate 15 normally arched from end to end and underlying the cushion for the greater part of its length, the plate having at its forward end a pair of diverging arms between which the cushion is unsupported, slots in the plate 20 in its region of the foot arch whereby the

plate may flex more easily at that point, and means for securing one end of the plate fixedly to the cushion and the other end adjustably thereto whereby to vary the curvature of the resulting arch in the support. 25

3. In a foot support, the combination of an arched plate, a cushion rested thereupon, a fixed connection between the cushion and the plate at one point, an adjustable connection between the plate and the cushion at another point, said latter connection including a block which is embedded within the cushion in a manner to be removable only from its upper side, there being a plurality of screw-threaded openings in the block, and other openings differently spaced in the plate, and a screw entered through one of the plate openings for engagement within a selected opening of the block. 30 35
